UNITED STATES PATENT OFFICE.

FREDRICK EDLUND, OF LANSE, PENNSYLVANIA.

GARMENT-HANGER.

989,587.

Specification of Letters Patent.

Patented Apr. 18, 1911.

Application filed November 17, 1910. Serial No. 592,838.

To all whom it may concern:

Be it known that I, FREDRICK EDLUND, a citizen of the United States, residing at Lanse, in the county of Clearfield and State 5 of Pennsylvania, have invented certain new and useful Improvements in Garment-Hangers, of which the following is a specification.

This invention relates to garment hangers and its object is to produce a device of this 10 kind that is simple and cheap to manufacture and that will occupy a small amount of space when in use.

With the foregoing and other objects in view the invention consists in the combination 15 and arrangement of parts to be hereinafter fully described in the following specification, pointed out in the claims and illustrated in the accompanying drawings which form a part of said specification and 20 in which—

Figure 1 is a side elevation illustrating the device in one position. Fig. 2 is a similar view showing one member at right angles to the position given it in Fig. 1. Fig. 3 is 25 an end view showing one member in section.

Like reference characters indicate corresponding parts throughout the several views.

The device comprises two separate members one of which is designed to rest in a 30 vertical position while supporting a garment and the other to rest in a horizontal position. The horizontal member is constructed to be supported by the vertical member in 35 either of two positions. Fig. 1 illustrates one position of the horizontal member in which its loop shaped extremities lie flat and Fig. 2 illustrates its position at right angles thereto in which the loop shaped extremities appear to stand on edge.

The vertically disposed member which I 40 shall designate as 1 is formed of two strands of wire or like material wound upon each other at one extremity and shaped into a hook 2 by which the member is suspended. These strands of wire form a shoulder 3 at the lower termination of hook 2 below which

shoulder they branch away from each other and form a pair of approximately parallel garment supporting frames 4 the lower extremity of each of which frames forms an elongated loop 5. A shoulder 6 is formed in one of the members 4 for the support of the horizontal member.

The horizontal member which I shall designate as 7 is formed of a single strand of wire bent to form terminal loops 8 and a centrally disposed loop 9, the wire being wound upon itself at 10, 10 which points are between the central loop and terminal 60 loops. The horizontal member 7 may be supported upon the vertical member by inserting the hook 2 through the loop 9 and resting said loop on shoulder 3 as illustrated in Fig. 1 in which instance the terminal loops 8 will lie flat and the horizontal member is then adapted for supporting a coat over these loops or other garments of a similar nature. A pair of trousers or a 65 dress skirt may be supported upon the elongated loop 5 of the vertical member.

In Fig. 2 the horizontal member is supported through the medium of the loop 9 inserted between the members 4 until it rests upon the shoulder 6 in which position 75 the terminal loops are adapted for holding stockings, gloves, or for other garments requiring a support of this kind.

What I claim is:—

1. A garment hanger comprising, a vertical member provided at one end with a hook, a shoulder formed at the lower termination of said hook, a pair of parallel members 4 formed below said shoulder, one of said members being formed with a shoulder 6 and a horizontal member 7 adapted to be supported by the vertical member upon either of its shoulders 3 or 6.

2. A garment hanger comprising, a vertical member provided at one end with a hook, a shoulder formed at the lower termination of said hook, a pair of parallel members 4 formed below said hook and each terminating in an elongated loop, one of

said members 4 being provided with a shoulder 6, a horizontally disposed member provided with terminal loops and a central loop which latter is designed for engagement 5 with one of the shoulders of the vertical member.

In testimony that I claim the foregoing

as my own I have hereto affixed my signature in the presence of two subscribing witnesses.

FREDRICK EDLUND.
